Primary Examiner—Paula A. Mortimer(74) *Attorney, Agent, or Firm*—Lawrence P. Trapani(57) **CLAIM**

The ornamental design for a desk calendar leaf, as shown and described.

DESCRIPTION

FIG. 1 is a front elevation view of a desk calendar leaf showing our new design; and,

FIG. 2 is a rear elevation view thereof.

The desk calendar leaf is flat and of conventional thickness. The broken line showing of the text in FIGS. 1 and 2 is for illustrative purposes only and forms no part of the claimed design.
